DESIGN FOR A TEXTILE FABRIC OR SIMILAR ARTICLE OF MANUFACTURE

John F. Gaul, Jr., Clifton, N. J., assignor to
Botany Worsted Mills, Passaic, N. J., a corporation of New Jersey

Application June 19, 1936, Serial No. 63,391

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic feature of the present design resides in a plain base fabric, which is loosely woven, resulting in a rough or crepe-like appearance, and series of horizontally disposed lines or ribs formed of a multiplicity of thickened threads spirally arranged, said lines or ribs being arranged over the surface of the fabric and being of substantially equal length and separated by substantially equal spaces horizontally of the fabric as shown.

I claim:

The ornamental design for a textile fabric or similar article of manufacture substantially as shown and described.

JOHN F. GAUL, JR.
